PATTERN INDICATOR

Maurice Hendrick and Vardy M. Abernethy,
Cliffside, N. C.; said Abernethy assignor to
said Hendrick

Application November 16, 1939, Serial No. 304,816

6 Claims. (Cl. 139—317)

This invention relates to textile machinery and more especially to a mechanism which will enable an unskilled worker to duplicate and verify pattern chains for dobby looms. When cloth is woven by a dobby loom it is necessary to provide a chain corresponding to the pattern which is to be woven. This chain comprises a plurality of bars linked together, each bar having a plurality of pins or pegs therein. When the chain is placed in the dobby head for controlling a particular pattern the bars are caused to successively pass, step by step, beneath the dobby fingers which are raised by the pegs to cause corresponding loom harnesses to be actuated. These chains are often very long, especially where a complicated pattern is being woven, and since it is necessary to provide a chain of this type for each dobby loom, the chain manufacture becomes quite a problem where many looms are in operation.

Heretofore, wherever a pattern chain was being produced for a piece of goods, the designer would mark out on a print the manner in which the pins were to be positioned in each particular link of the chain. Then it was necessary for a skilled mechanic to take this print and construct the chain accordingly. If several chains were to be produced, the same amount of labor was necessary for each chain. In other words, a master chain had to be produced directly from the prints by a skilled worker for each dobby loom that was to be operated in the mill.

It is an object of this invention to provide a chain duplicating apparatus which can be operated by a master chain which chain is constructed by a skilled mechanic. This master chain will be placed in the apparatus hereinafter to be described, and as it passes through the apparatus it will actuate a suitable mechanism to indicate the location of the pins on a chain under construction which is simultaneously passed through the apparatus. Since the master chain can be passed through the apparatus as many times as desired, it is seen that any number of duplicate chains can be constructed and verified by unskilled labor.

It is another object of this invention to provide an apparatus of the class described having means for simultaneously passing therethrough a master pattern chain and a pattern chain to be constructed, with indicating wires disposed between the pattern chains and means for laterally shifting the pattern chains relative to the wires whereby the apparatus can be adapted for use on

pattern chains having a different pin hole spacing therein.

Some of the objects of the invention having been stated, other objects will appear as the description proceeds, when taken in connection with the accompanying drawings, in which—

Figure 1 is a front elevation of a pattern chain duplicating and verifying mechanism;

Figure 2 is an elevation looking at the right-hand side of Figure 1 and also showing the foot 10 operated actuating mechanism;

Figure 3 is a vertical sectional view taken along the lines 3—3 in Figure 1;

Figure 4 is a vertical sectional view taken along the line 4—4 in Figure 1;

Figure 5 is a plan view of one type of link with the pins removed which forms a portion of a pattern chain that is adapted to operate in the mechanism disclosed in the drawings;

Figure 6 is a plan view of another type of chain link which may be used in the apparatus, the pin hole spacing in this link being different from the pin hole spacings shown in Figure 5.

Referring more specifically to the drawings (Figure 5) the numeral 10 denotes a link which forms a part of a pattern chain for a dobby loom. This link has a plurality of holes 11 therein in which suitable pins 12 are adapted to be inserted. In the construction of pattern chains, the pins 12 are placed in certain holes and omitted in other holes so that a particular pattern will be woven when the chain is placed in a dobby head. The designer usually makes a print designating the particular location in each bar where the pins 12 are to be placed, then a skilled mechanic constructs the chain accordingly.

Each link of the chain has eyelets 14 secured at each end, and these eyelets are connected to each other by means of rings 15, so that a continuous chain can be formed. The biggest problem in the construction of these chains is the accurate placing of the pegs or pins 12 within the holes 11. As heretofore stated, the primary object of this invention is to eliminate as much skilled labor as possible in this chain construction. In the apparatus hereinafter to be described, it will be noted that only one chain, namely a master chain 16, will be constructed by a skilled mechanic and then as many exact duplicate chains as desired can be formed by unskilled labor merely by passing the master chain through the apparatus to serve as a guide or indicator while an operator affixes pins in the bars of a chain being made as a duplicate of the master chain. When the master chain 16 has been formed with all of the pegs

or pins 12 properly spaced therein, it is mounted upon spaced rollers 17, said rollers having flutes 18 in the peripheries to accommodate the links 10 of the chain. These rollers are fixedly secured 5 around the shaft 19 which in turn is rotatably mounted in brackets 20 and 21 secured to side frames 22 and 23 respectively. The brackets 20 and 21 have slots 24 and 25 therein which slots are penetrated by bolts 26 and 27 respectively for 10 adjustably securing the brackets in position upon the side frames 22 and 23.

The right-hand end of the shaft 19 has a sprocket 30 fixedly secured thereon. Upon this sprocket, a chain 31 is mounted which chain is 15 also mounted upon another sprocket 32 thereabove which is disposed upon a second shaft 33. This shaft 33 is rotatably mounted in brackets 34 and 35, said brackets being secured to side frames 22 and 23, respectively. It is therefore seen that 20 the two shafts 19 and 33 are caused to rotate in unison at the same rate of speed since the sizes of the sprockets 30 and 32 are identical. The position of the shaft 33 can be adjusted vertically very much in the same manner that vertical adjustment is provided for the shaft 19 therebelow. This adjusting means comprises slots 31 and 33 25 in the brackets 34 and 35 which slots are penetrated by stud bolts 39 and 40 respectively and the stud bolts have their ends threadably secured in the side frames 22 and 23.

Means have also been provided for taking up excess slack in the chain 31. This means comprises an idler pulley 45 (Figure 2) which is rotatably mounted upon stud shafts 46 extending from bracket 47 and the bracket 47 is secured to the side frames 23 by any suitable means such as stud bolt 48. When it is desired to vary the amount of slack in the chain 31 it is only necessary to loosen the bolt 48 and rotate the bracket 47 and its associated sprocket 45 to the desired position and then tighten the bolt.

The intermediate portion of the shaft 33 has spaced hubs 50 fixedly secured thereon, said hubs having a plurality of flutes 51 in the peripheries thereof, into which the links 10 of an embryonic pattern chain 52 are adapted to fit. The pattern chain 52 is the pattern chain which is under construction, and which is to constitute a duplicate of the master pattern chain 16 therebelow on the roller 17, when completed. In order 50 to construct the pattern chain 52 so that it will be identical to the master chain 16, a suitable indicating mechanism must be controlled by the pins 12 within the chain 16 to designate the corresponding position on chain 52. This indicating mechanism comprises a plurality of fingers 54 which are pivoted at one end to a shaft 55, said shaft being disposed between the side frames 22 and 23. The spacing of fingers 54 upon the shaft 55 is one-half the spacing of the holes 11 in the bars 10 (Figures 1 and 5). Therefore, when a chain having pin hole spacing, as shown in Figure 5, is used only every other finger will serve a useful purpose. However, the excess number 60 of fingers will be used when a chain is being constructed having bars with a closer pin spacing such as the bar shown in Figure 6. These fingers have their free ends (Figure 3) normally disposed above the rollers 17 and the master chain 16 so that the pins 12 within the chain will pass beneath the fingers and cause them to be rotated upwardly and about the shaft 55. When a pin 12 is not disposed beneath a finger 54 the free ends thereof are adapted to rest upon a horizontally disposed bar 56 which is disposed be-

tween the side frames 22 and 23. The free ends of the fingers 54 are separated and held in position against lateral movement by suitable upstanding pins 57 which have their lower ends mounted in the bar 56.

Resting upon the free end of each of the fingers 54 is a U-shaped wire 60, mounted for vertical sliding movement in plate 61, said plate being pivoted upon a shaft 62 which is supported by the side frames 22 and 23. The upper 10 ends of the wires 60 are disposed in close proximity to the upper rollers 51 and also in close proximity to the links of chain 52 as they pass thereby. For example, when a link 10 in the chain 16 is disposed in uppermost position on 15 hubs 17 (Figure 3) an upstanding pin 12 will actuate the corresponding finger 54 to cause the upper end of a wire 60 to be raised above the upper edge of plate 61 and to a position close to a hole in one of the links of chain 52. When the 20 wire is thus raised, it is only necessary for an unskilled laborer to insert a pin in the indicated hole. In other words, each time a link of master chain 16 passes beneath the fingers 54, the pins 25 therein will serve to raise wires 60 so that the pins can be placed in the links of the chain 52 which is under construction at a corresponding position; consequently the chain 52 under construction will be identical to the master chain 16 therebelow.

The shafts 19 and 33 together with their respective rollers 17 and 50 are normally rotated in a clockwise direction, step by step, one chain link at a time. For example, when the master chain 16 is advanced one link the chain 52 under construction is advanced a link by means of the sprockets 30 and 32 and the connecting chain 31. This advancing may be effected manually by means of hand wheels 65 or 66, or it may be effected by means of a suitable foot operated mechanism as shown in Figure 2. This foot operated mechanism comprises a ratchet 68 which is fixedly secured upon shaft 19. The teeth in the ratchet 68 are adapted to be engaged by a pawl 69, the lower end of which is pivoted as at 70 to a horizontally disposed lever 71. This lever 71 is pivoted as at 72 to the frame 23. A spring 75 normally holds the hook on the upper end of pawl 69 out of engagement with the teeth of ratchet 68.

Connected to the lever 71 and pawl 69 as at 70 is a downwardly depending link 74 and the lower end of this link is pivoted as at 75 to the intermediate portion of a foot lever 76, said lever having one end thereof pivoted as at 77 to a supporting table 78 which table is adapted to support the indicating mechanism. It is seen by referring to Figure 2 that when pressure is applied to the free end of the foot lever 76 the pawl 69 will engage a notch in the ratchet 68 to cause 60 the shafts 19 and 33 together with their associated hubs 17 and 50 to rotate in a clockwise manner. Since there are eight flutes in each of the rolls 17 and 50, and since there are also eight notches in the ratchet 68 it is evident that for 65 each foot operation, each of the rolls 17 and 50 will be advanced exactly one flute and this will mean that for each operation the chains 16 and 52 will be advanced upon each roller a distance of one link.

In order to insure that the rollers 17 and 50 will remain in position after each operation so that the pins can be inserted in the chain 52 under construction, it is necessary to provide suitable notched disks 80 and 81 upon the shafts 75

19 and 33 respectively (see Figures 1 and 4). The notches in these disks are adapted to be engaged by rollers 82 and 83 on the levers 84 and 85 which levers are pivoted as at 86 and 87 respectively to side frames 22. Springs 88 and 89 are provided to normally hold the rollers 82 and 83 in engagement with the notches of disks 80 and 81 respectively. Of course when it is desired to advance the rollers 17 and 50 a distance of one chain link, the rollers 82 and 83 will be forced out of their notches and then allowed to fall into the next succeeding notch in their respective disks. The springs 88 and 89 are sufficiently weak to allow this action to take place and yet they are sufficiently strong to hold the rollers and their respective shafts in position while the pins 12 are being inserted within the links of the chain 52 which is under construction.

20 By referring to Figures 2 and 3, it will be seen that the plate 61 which holds the indicating wires 60 can be adjusted to move the upper ends of the indicating wires toward or away from the bars of the chain 52. This adjusting mechanism comprises an eccentric 90 which is secured to the inside face of the frame 23. The periphery of this eccentric is adapted to support the upper end of plate 60. When it is desired to increase the distance that the upper ends of the indicating wires 60 occupy relative to the bars in the chains 52, it is only necessary to turn the eccentric 90 and thereby rotate the plate 60 in a counterclockwise manner about the shaft 62.

35 It will also be noted by referring to Figures 2 and 3 that an apron 92 is provided beneath the chain 52 at a position between the rollers 17 and 50. This apron primarily serves to prevent the upper chain 52 from becoming entangled with the chain 16 therebelow and the supporting means for this apron comprises the shaft 55 upon which the dobby fingers 54 are mounted.

Figure 6 shows a slightly different form of link 94 which is used in dobby loom chains. This 45 link has a plurality of staggered holes 95 therein into which pins 12 are adapted to be inserted. The spacing of the holes 95 is slightly different from the spacing of the holes 11 in the link 10 as shown in Figure 5. When a chain formed of 50 links of this type is used in the above described mechanism, it is necessary to shift the hubs 17 and 50 relative to the indicating wires 60 and laterally of the apparatus so that the upper ends of these wires, when actuated, will coincide with 55 the desired holes 95 in the bar. When a chain made of the bars 10 is being used, the shafts 19 and 33 and their corresponding hubs 17 and 50 are shifted to their extreme right-hand positions as shown in Figure 1, but when a chain 60 made of links 94 as shown in Figure 6 is being used, it is necessary to shift the shafts and their rollers slightly to the left to cause the indicating wires to properly coincide with the holes in the chain under construction.

65 The mechanism for shifting the shafts 19 and 33 together with their hubs 17 and 50 comprises a vertically disposed bar 100, the central portion thereof being penetrated by an elongated shaft 101. The upper ends of bar 100 fit against 70 the faces of disk hubs 80 and 81 respectively. Around the shaft 101, a compression spring 102 is mounted which has one end thereof abutting against the bar 100 and its other end abutting against the frame 22. Shaft 101 is slidably 75 mounted in the frames 22 and 23 and has a col-

lar 103 fixedly mounted on the intermediate portion thereof at a point close to the inside face of frame 22. A lever 104 is also pivoted to the inside face of frame 22 as at 105. The lower end of this lever has a notch 106 therein which 5 is adapted to partially encircle the shaft 103. Also the lower edge of the lever 104 at the notch 106 is provided with cam faces 107 which serve to wedge in between the collar 103 and the inside face of the frame 22, and thereby cause the 10 shaft 101 together with the bar 100, shafts 19 and 33, and the rollers 17 and 50 to be moved to the right in Figure 1. Of course when the lever 104 is rotated in a counter-clockwise manner in Figure 4, the shaft 101 together with its 15 associated parts are moved to the left in Figure 1 under the force of compression spring 102. In other words, when the lower end of lever 104 is disposed between the collar 103 and the 20 frame 22, the rollers 17 and 50, together with the corresponding chains 16 and 52, are moved to the extreme right hand position in Figure 1; whereas when the lower end of the lever 104 is moved from between the members 22 and 25 103, the compression spring 102 will move the rollers 17 and 50 together with their corresponding chains to the extreme left hand position. This shift merely provides a minute adjustment as to the position that the upper ends of indicating wires occupy relative to the holes within 30 the bars of the chain under construction.

When it is desired to vary the over-all length of the rollers 17 and 50 to accommodate chains having longer or shorter links therein it is only necessary to loosen the screws 11a and 50a to 35 adjust the positions of the bottom and top rollers on shafts 19 and 33 to accommodate the length of chain which is being used.

Another important use of the above described apparatus is that of rebuilding dobby chains. It 40 is a well known fact that a large percentage of new chains in mills are built from old ones simply by re-arranging or shifting the pegs from one hole to the other in the bars. By making additions and subtractions where necessary in the 45 old chain, the amount of labor is considerably less, because many patterns have a good bit of similarity; consequently many of the pins in the old chains do not have to be disturbed. Of course the re-worked chain is placed on the top cylinder 50 50 and the master chain is placed in the bottom cylinder 17.

In the drawings and specification, there has been set forth a preferred embodiment of the invention, and although specific terms are employed, they are used in a generic and descriptive sense only and not for purposes of limitation, the scope of the invention being set forth in the appended claims.

We claim:

1. Mechanism for use in duplicating a dobby chain for looms, comprising a rotatable member for holding a completed dobby chain having bars and pegs therein, a second rotatable member for holding a dobby chain devoid of pegs but whose 65 bars have holes therein corresponding to the holes in the bars in the dobby chain having pegs, means for rotating the two chains step by step, a plurality of indicators movable by the pegs in the completed chain into close proximity to the 70 holes in the other chain to indicate where pegs are to be placed.

2. Mechanism for use in duplicating a dobby chain for looms, comprising a rotatable member for holding a completed dobby chain having bars 75

- and pegs therein, a second rotatable member for holding a dobby chain devoid of pegs but whose bars have holes therein corresponding to the holes in the bars in the dobby chain having pegs, 5 means for rotating the two chains step by step, a plurality of indicator fingers movable by the pegs in the completed chain into close proximity to the holes in the other chain to indicate where pegs are to be placed, and means for shifting the 10 chains laterally of the indicators to cause other pegs in the completed chain to actuate other indicators to indicate additional holes in the other chain where pegs are to be placed.
3. Indicating apparatus for use in the formation of pattern chains for looms, wherein the pattern chains comprise a plurality of parallel bars linked together in spaced relation and having a plurality of holes therein for the reception of pegs, rotatable means for holding a completed 15 pattern chain, other rotatable means for holding a pattern chain devoid of pegs but having holes in its bars, means for intermittently advancing both pattern chains, a plurality of indicating fingers movable by pegs in the completed pattern chain into close proximity to the holes in the bars 20 of the incomplete pattern chain to indicate which holes in the incomplete chain are to receive pegs.
4. Indicating apparatus for use in the formation of pattern chains for looms, wherein the pattern chains comprise a plurality of parallel bars linked together in spaced relation and having a plurality of holes therein for the reception of pegs, rotatable means for holding a completed pattern chain, other rotatable means for holding a 25 pattern chain devoid of pegs but having holes in its bars, means for intermittently advancing both pattern chains, a plurality of indicating fingers movable by pegs in the completed pattern chain into close proximity to the holes in the bars 30 of the incomplete pattern chain to indicate which holes in the incomplete chain are to receive pegs, means for shifting both of the pattern holding 35 means along their longitudinal axes to thereby cause the indicator fingers to be moved upwardly by pegs in a pattern chain having pegs arranged differently from those in the preceding form, and means for yieldingly holding both of the pattern holding means in position while pegs are inserted 40 in the incomplete pattern chain.
5. Indicating apparatus for use in the formation of pattern chains for looms, wherein the pattern chains comprise a plurality of parallel bars linked together in spaced relation and having a plurality of holes therein for the reception of pegs, rotatable means for holding a completed pattern chain, other rotatable means for holding a pattern chain devoid of pegs but having holes in its bars, means for intermittently advancing both pattern chains, a plurality of indicating fingers movable by pegs in the completed pattern chain into close proximity to the holes in the bars 15 of the incomplete pattern chain to indicate which holes in the incomplete chain are to receive pegs, means for yieldingly holding both of the pattern holding means in position while pegs are inserted 20 in the incomplete pattern chain.
6. Indicating apparatus for use in the formation of pattern chains for looms, wherein the pattern chains comprise a plurality of parallel bars linked together in spaced relation and having a plurality of holes therein for the reception of pegs, rotatable means for holding a completed pattern chain, other rotatable means for holding a pattern chain devoid of pegs but having holes in its bars, means for intermittently advancing both pattern chains, a plurality of indicating fingers movable by pegs in the completed pattern chain into close proximity to the holes in the bars 25 of the incomplete pattern chain to indicate which holes in the incomplete chain are to receive pegs, means for shifting both of the pattern holding 30 means along their longitudinal axes to thereby cause the indicator fingers to be moved upwardly by pegs in a pattern chain having pegs arranged differently from those in the preceding form, and means for yieldingly holding both of the pattern holding means in position while pegs are inserted 35 in the incomplete pattern chain.
- MAURICE HENDRICK,
WARDY M. ABERNETHY.
